UNITED STATES PATENT OFFICE.

HENRY DE SMITH, OF ROCHESTER, NEW YORK, ASSIGNOR TO M. D. KNOWLTON COMPANY, OF ROCHESTER, NEW YORK, A CORPORATION OF NEW YORK.

SAFETY OPERATING MECHANISM.

Application filed August 13, 1919. Serial No. 317,238.

To all whom it may concern:

Be it known that I, HENRY DE SMITH, a citizen of the United States, and resident of Rochester, in the county of Monroe and State of New York, have invented certain new and useful Improvements in Safety Operating Mechanism, of which the following is a specification.

This invention relates to safety operating mechanism for box making or other machines which employ a movable presser member, and has for its object to provide an improved safety operating mechanism designed to preclude the possibility of the operator's hand or fingers becoming injured by the presser member during the operation of the machine.

The invention, while applicable to machines of various kinds, is here shown as incorporated in the box-form of a box-ending machine. In these machines, the box-form is mounted on a reciprocating carrier and is caused to co-operate with a stationary presser member to press an interposed end blank onto the end flanges of a box blank carried by the form. In accordance with the preferred form of my invention here shown, the box-form is made in two sections, one being adapted to be rigidly connected to the form carrier and the other being movable relatively thereto. Associated with this sectional form are automatic means which are normally operative to maintain the outer or presser section in yielding relation to the other until just prior to the form reaching a position for pressing engagement with the work, and to then effect a positive connection between the sections to hold the presser one in fixed or unyielding relation to the other. Thus, if any obstruction, such as the operator's hand or fingers, is encountered during the working stroke of the form, no harm will be done as the outer or presser section of the form at that time is in yielding relation to the other section and its actuating means. If, however, no obstruction lies in the path of the moving form, the automatic means will operate to render the presser section unyielding relatively to the other just before it reaches its work-pressing position and so cause it to perform its work-pressing function.

One form of automatic means operative in the way referred to is made the subject of reissued Letters Patent No. 15,611, dated

May 22, 1923, and comprises a plurality of connections between the upper and lower form sections which are rotatable to and from their operative positions for holding the upper form section rigid relatively to the lower one. In accordance with my present invention, however, I provide connections between the form sections which are adapted for sliding movement to and from their operative holding positions. Also, as a further and important feature of my present invention, I provide automatic means, which is positive in its action, for returning the connections between the upper and lower form sections to their inoperative positions following the work-performing operation of the presser members, thus positively assuring the upper or presser member being in yielding or safety relation to the lower or supporting one during such time in the operation of the machine that an operator's hand or fingers might become caught between the presser members.

Referring now to the accompanying drawings forming part of this specification—

Fig. 1 is a sectional side elevation of a box-ending machine having a box-form embodying my invention mounted on the reciprocating carrier thereof.

Fig. 2 is an enlarged plan view of the box-form removed from the carrier, with part of the same broken away for the clearer illustration of certain of the parts.

Fig. 3 is a side elevation of the same on a reduced scale, also with part of the same broken away for the clearer illustration of certain of the parts.

Fig. 4 is an end view of the same looking from the left as viewed in Fig. 3.

Fig. 5 is a perspective view of a box blank as it appears prior to having the ends applied thereto.

The box-ending machine here shown is of substantially usual construction and comprises a frame 2 in which is journalled a crank shaft 3 connected through suitable gearing 4—5 with a drive-shaft 6 carrying a belt-pulley 7. Connected with the frame 2 for vertical reciprocation is a box-form carrier 8 which is actuated from the crank shaft 3 through a pitman connection 9. In the operation of the machine, a box blank having inwardly turned flanges, such as shown in Fig. 5, is placed on the box-form with the flanges at one end resting upon the

2
top of the form. An end blank, to which adhesive has been applied, is then fed by the machine in usual manner to a position on top of these flanges, after which the form 5 is raised to cooperate with the upper head or presser member 10 of the machine to press the end blank onto the box flanges. In manipulating the work in the operation 10 of these machines, it sometimes happens that the operator gets his hand or fingers caught between the top of the box-form and the co-operating presser member 10, with resulting injury to them. To provide an improved means for preventing the possibility of 15 this has been the purpose of the present invention.

The box-form comprises two main sections, the lower one, indicated at 11, being adapted to be rigidly attached to the carrier 20 in any usual or suitable manner, and the upper section, indicated at 12, being adapted for the direct support of the box blank.

The upper section 12, which is made up of adjustable parts as will hereinafter be 25 described, is yieldingly supported in a normally projected position above the lower one by means of springs 13 located at the four corners thereof. As a means for guiding the upper section when moved vertically relatively to the lower one, as permitted by these springs, guide-pins 14 are provided at the four corners of the form which are attached at their upper ends to the upper section by suitable fastening means, such as the screws 15, and at their lower ends extend and work in guide openings 16 in the lower section. As a means to limit the upward movement of the upper section relatively to the lower one under the action of the springs 30 13, pins or screws 17 on the lower section are arranged to engage with suitable stop shoulders 18 on the guide-pins, as shown in Fig. 3. These guide-pins in the present case are made tubular to receive the upper ends of 35 the springs 13, which latter at their lower ends are located in the guide openings 16 in the lower section. In this way the springs are housed and protected from injury.

The upper section of the form is yieldingly held relatively to the lower one and its actuating carrier during the upward movement of the form until the latter reaches a 40 point in close proximity to the upper presser member 10, say to a point within approximately one-quarter of an inch therefrom or so close as to prevent the entry of a person's hand or fingers, at which time it is necessary to render said upper section rigid or unyielding relatively to the lower one, whereby it will be caused to exert the necessary pressure upon the interposed work. The means here shown for doing this comprise two members 20, 20, slidably mounted 45 on the lower section adjacent opposite sides

thereof and each provided with lateral projections 22, 22, adapted to be shifted by a longitudinal sliding movement of the members 20 to and from their supporting positions beneath depending lugs 23, 23, on the 70 upper form section. When these members are in inoperative position with their projections 22 withdrawn from supporting position beneath the lugs 23 of the upper form section, as shown in Fig. 3, the upper section may yield relatively to the lower one as there is nothing between them at such time to prevent collapsing other than the springs 13 which yieldingly hold the upper section in its normally projected position. 75

As a means for sliding these members to their operative supporting positions at the desired time in the operation of the machine, I attach to the lower form section adjacent the rear ends of said sliding members, a pair of brackets 25, 25, in each of which is pivotally supported, at 26, a bell crank 27 arranged to engage at one end with the end of the adjacent member 20, as shown in Fig. 3. In a vertically arranged tubular extension 28 of each of the brackets 25 is supported a means for operating the adjacent bell crank, which means is here shown as comprising an operating member or pin 29 slidably supported at the upper end of the 80 tubular extension and engaging with the bell crank through an interposed spring 30 and slide 31, the latter having a pin or projection 32 at its lower end engaging directly with the bell crank. As will be obvious, downward pressure on the members 29 will operate to swing the bell cranks on their pivots in a direction to advance the members 20 to operative supporting positions with their projections 22 beneath the depending lugs 23 of the upper form section. In order to have this operation take place at the desired predetermined time, the operating members 29 project above the plane of the 85 upper surface of the box-form a distance of approximately one-quarter of an inch, whereby they will be operated by engagement with the stationary presser member 10 just before the box-form reaches its position 90 for pressing engagement with the work.

During the upward movement of the box-form, the members 20 will be maintained in their inoperative positions with the projections 22 withdrawn from beneath the lugs 23, whereby the upper form section 95 may yield relatively to the lower one, until the operating members 29 come into contact with the upper stationary member 10, either directly or through an interposed end blank, after which continued upward movement of the form will cause said operating members 29 to advance the sliding members 20 to their operative positions with the projections 22 beneath the lugs 23 of the upper form 100 section. When thus supported, the upper 105

form section becomes rigid or unyielding with relation to the lower one and is therefore caused, upon the continued upward movement of the form, to co-operate with 5 the stationary member 10 to exert the required pressure upon the interposed work. If, however, an obstruction of greater thickness than the length of the projecting ends of the operating members 29, such, for instance, as the operator's hand or fingers, becomes accidentally caught between the box-form and the stationary presser member 10 during the upward movement of the box-form, the upper form section will be stopped 10 in its movement upon the obstruction contacting with the stationary presser member 10 and thereby permit the projections 22 on the slide members 20 to move up past the lower ends of the lugs 23 on said upper 15 form section, where they will be held inoperative and against further lateral movement when the operating members 29 are subsequently brought into engagement with the stationary presser 10. The springs 30 interposed between the operating members 29 and the bell cranks 27 will yield at such times, i. e. when the members 20 are held 20 against sliding movement by the engagement of the projections 22 with the vertical sides 25 of the lugs 23, and prevent breakage or other damage of the parts.

Upon the descent of the box-form following its pressing engagement with the work, the members 20 are returned to their inoperative positions of disengagement with the upper form section by suitable automatic means. This means, as here shown, comprises a pair of springs 35, 35, which at one end engage said members within recesses 30 36 therein and at their opposite ends engage 40 stationary screws 37 set in the form, as shown.

The box-form may be made up in any suitable or desired way. As here shown, it is made adjustable to receive box blanks 45 of different sizes. In providing for this adjustment, the upper form section 12 is made up of a pair of laterally adjustable side members 40, 40, having inwardly projecting extensions 41 at one end slidably connected 50 with an end member 42, and the lower section 11 is made up of a base 43, adapted for attachment to the carrier 8, and a pair of plates 44, 44, slidably mounted thereon for lateral adjustment; these plates 44 on the base 43 being provided to carry the 55 lower ends of the connections between the upper and lower form sections, such as the guides 14 and associated springs 31, and the sliding supports 20 and their respective 60 operating means. As clearly shown in Fig. 2, each member 20 and its operating means, including the spring 35 for moving said member in one direction, and the sliding pin 29 and intermediate connections for 65 moving it in the opposite direction, are

mounted as a unit on one of the plates 44 for lateral adjustment relative to the other.

As a means for adjusting the width of the form, an endwise-stationary screw 45 is provided, having right and left hand screw 70 threads engaging the opposite plates 44, 44. Rotary movement being imparted to this screw, as by means of a wrench applied to either of its squared ends, will cause a lateral movement of the opposite sides of 75 the form toward or from each other, as desired. After the desired adjustment of the form has been effected, the parts may be secured in adjusted position by suitable fastening means, such as the screws 46, 80 which engage the lower plates 44, and the screws 47, which connect the extensions 41 of the upper members 40 with the end member 42. An annular collar 48 at the center of the screw 45 engages the base 43 within 85 an opening 49 therein to hold the screw against endwise movement.

As hereinbefore described, the springs 35 operate to automatically return the sliding supports 20 to their inoperative positions of 90 disengagement with the upper form section upon the down stroke of the form. If, however, these springs for any reason fail to properly operate, the members 20 would remain in their operative supporting positions and so prevent the upper form section 95 from yielding in the performance of its safety function. Therefore, I have provided an additional or supplemental means for returning the members 20 to their inoperative positions, which is positive in its action.

This means comprises a link 50, which is pivotally connected at one end with a stationary support, as at 51, and at its opposite end is operatively connected with 100 the members 20 to slide them to their inoperative positions upon the downward movement of the form. As here shown, the connection of the link with said slide members 20 is made by means of a transverse pin 52 at the inner end of the link slidably engaging at its opposite ends with tubular members 53, 53, connected with said slide members; this connection permitting of the described lateral adjustment 105 of the form. A forked stud 54 on the base 110 of the form engages the link 50 and holds it centrally of the form during operation and adjustment of the parts.

The tubular members 53 engage the slide members 20 within longitudinally extending slots 55 therein. These slots are so formed as to permit of the slide members 20 being moved to their operative supporting positions under the action of the pins 29 when 120 brought into engagement with the upper presser member 10, at which time the link connections 53 will be at the right hand end of the slots in the members 20, as shown in 125 Fig. 2. Thereafter, upon the downward 130

movement of the form the connecting end of the link 50, moving downwardly and laterally in the arc of a circle, operates to positively return the members 20 to their 5 inoperative positions with the projections 22 withdrawn from beneath the lugs 23.

The tubular members 53 may be slidably connected with the members 20 in any suitable manner, the same as here shown being 10 provided with annular recesses in which the walls of the slots 55 engage as shown.

Having thus set forth one practical embodiment of my invention, what I claim and desire to secure by Letters Patent is:—

1. In a box-ending machine, the combination with the presser-head and the vertically reciprocating box-form carrier, of a box-form mounted on said carrier comprising upper and lower sections, means 15 yieldingly holding the upper section in a normally projected position above the lower one, a slideable connecting member between said sections which is capable of being rendered operative and inoperative to maintain the upper section unyielding relatively to the lower one, means for controlling the action of the connecting member to render it operative just prior to the box-form reaching the end of its working stroke, said means including an operating member carried by the reciprocating box-form and actuated by engagement with a cooperative stationary part, and positively acting automatic means for rendering the connecting member 20 inoperative on the down stroke of the carrier following the work-performing operation.

2. In a box-ending machine, the combination with the presser-head and the vertical reciprocating box-form carrier, of a box-form mounted on said carrier comprising upper and lower sections, means yieldingly holding the upper section in a normally projected position above the lower one, a slideable connecting member between said sections which is capable of being rendered operative and inoperative to maintain the upper section unyielding relatively to the lower one, means for controlling the action of the connecting member to render it operative just prior to the box-form reaching the end of its working stroke, said means including an operating member carried by the reciprocating box-form and actuated by engagement with a cooperative stationary part, and means for automatically rendering the connecting member inoperative on the down stroke of the carrier following the work-performing operation.

3. In a box-ending machine, the combination with the presser-head and the vertically reciprocating box-form carrier, of a box-form mounted on said carrier comprising upper and lower sections, means yieldingly holding the upper section in a normally pro-

jected position above the lower one, a slideable connecting member between said sections which is capable of being rendered operative and inoperative to maintain the upper section unyielding relatively to the lower one, means for controlling the action of the connecting member to render it operative just prior to the box-form reaching the end of its working stroke, said means including an operating member carried by the reciprocating box-form and actuated by engagement with a cooperative stationary part, and positively acting automatic means for rendering the connecting member inoperative on the down stroke of the carrier following the work-performing operation.

4. In a box-ending machine, the combination with the presser-head and the vertically reciprocating box-form carrier, of a box-form mounted on said carrier comprising upper and lower sections, means yieldingly holding the upper section in a normally projected position above the lower one, a connecting member between said sections which is capable of being rendered operative and inoperative to maintain the upper section unyielding relatively to the lower one, means for controlling the action of the connecting member to render it operative just prior to the box-form reaching the end of its working stroke, said means including an operating member carried by the reciprocating box-form and actuated by engagement with a cooperative stationary part, and positively acting automatic means for rendering the connecting member inoperative on the down stroke of the carrier following the work-performing operation.

5. In a box-ending machine, the combination with the presser-head and the vertically reciprocating box-form carrier, of a box-form mounted on said carrier comprising upper and lower sections, means yieldingly holding the upper section in a normally projected position above the lower one, a slideable connecting member between said sections which is capable of being rendered operative and inoperative to maintain the upper section unyielding relatively to the lower one, means for controlling the action of the connecting member to render it operative just prior to the box-form reaching the end of its working stroke, said means including an operating member carried by the reciprocating box-form and actuated by engagement with a cooperative stationary part, and positively acting automatic means for rendering the connecting member inoperative following the work-performing operation, said means including a pivoted linkage between said connecting member and a stationary support.

6. In a box-ending machine, the combination with the presser-head and the vertically reciprocating box-form carrier, of a box-

form mounted on said carrier comprising a box supporting section, means yieldingly holding said section in a normally projected position above the carrier, a slidable connecting member between said section and the carrier which is capable of being rendered operative and inoperative to maintain the section unyielding relatively to the carrier, means for controlling the action of the connecting member to render it operative just prior to the box-form reaching the end of its working stroke, and positively

acting automatic means for rendering the connecting member inoperative on the down stroke of the carrier following the work- 15 performing operation.

Signed at Rochester, in the county of Monroe, and State of New York, this 11th day of August, A. D., 1919.
